[57] **CLAIM**

The ornamental design for a bow, as shown and described.

DESCRIPTION

FIG. 1 is a top view illustrating our new design;
FIG. 2 is a bottom view thereof;
FIG. 3 is a front elevational view thereof;
FIG. 4 is a rear elevational view thereof;
FIG. 5 is a left side view thereof;
FIG. 6 is a right side view thereof; and,
FIG. 7 is a top view thereof, on a scale smaller than that
shown in FIG. 1, the additional bows shown in broken lines
are for illustrative purposes only, and form no part of the
claimed design.
